UNITED STATES PATENT OFFICE.

ALBERT H. JOHNSON, OF WASHINGTON, DISTRICT OF COLUMBIA, ASSIGNOR TO NATIONAL ELECTRICAL SUPPLY COMPANY, OF WASHINGTON, DISTRICT OF COLUMBIA, A CORPORATION OF VIRGINIA.

TRANSMITTING APPARATUS FOR WIRELESS TELEGRAPHY.

1,145,066.

Specification of Letters Patent.

Patented July 6, 1915.

Application filed November 14, 1912. Serial No. 731,382.

To all whom it may concern:

Be it known that I, ALBERT H. JOHNSON, a citizen of the United States, residing at Washington, in the District of Columbia, have invented certain new and useful Improvements in Transmitting Apparatus for Wireless Telegraphy, of which the following is a specification.

This invention relates to certain new and useful improvements in transmitting apparatus for wireless signaling which, while adapted for general use in the art, are particularly valuable and important in their application to portable generating sets for wireless telegraphy.

An important object of this invention is to provide transmitting apparatus for wireless telegraphy which can be operated with the minimum application of power.

Another object of this invention is to provide a portable, manually operated, preferably self contained generating set for wireless transmission which is light in weight, simple in construction, convenient to use and capable of providing current for wireless communication throughout a wide area.

Other objects and advantages of this invention will be apparent from the following specification wherein reference is made to the accompanying drawings showing, for purposes of illustration, a diagrammatic view of transmitting apparatus and circuits thereof involving my invention.

In the drawing, 1 represents the armature winding of a generator or exciter 2, preferably a shunt wound direct current generator or exciter, having brushes 3 and 4 separately connected in parallel as shown with the field 5 of the exciter 2 and with the field 6 of a generator 7, preferably an alternating current generator, whose armature 8 is mechanically connected by the shaft 9 with the armature 1. The armature windings 1 and 8 are preferably wound upon the same armature shaft. A transmitting key 10 is included in circuit with the armature winding 1 and the field 6.

The brushes 11 and 12 of the generator 7 are connected, as shown, with the primary winding 13 of a transformer 14. The ends of the secondary winding 15 of the transformer 14 may be connected respectively with the aerial conductor A and with the earth connection E, these conductors being

in electrical communication with the spark gap 16, in accordance with the usual practice.

The shaft 9 carrying the armature windings of the generators 2 and 7 may be rotated by any suitable means. In the preferred form of my invention the shaft 9 is manually operated by means of the cranks 17 and 18 mounted upon the ends of a suitably supported shaft 19 which may carry a large sprocket wheel 20, power 60 being supplied to a small sprocket 21 on shaft 9 by means of a sprocket chain 22. Each crank is designed and arranged to be operated by one or more men. Mounted upon the armature shaft 9 is a fly wheel 23 70 which in my invention serves the important purpose of storing up energy when the transmitting key 10 is open, and the shaft 9 accordingly capable of being easily rotated, and giving out energy when the transmitting key 10 is closed and the armature shaft requires more power to effect its rotation.

The method of operation of my apparatus is as follows: The armature shaft 9 being rotated by any suitable means preferably manually by the operation of the cranks 17 and 18, current is generated in the armature winding 1 and its field 5 is energized. When the transmitting key 10 is open there is no circulation of current from the exciter 2 through the field 6 of the generator 7 and, consequently little resistance is offered to the rotation of the armature 8. The shaft 9 is relatively easily rotated and considerable energy may be stored up in the 90 fly wheel 23. When the transmitting key 10 is closed the field 6, of the generator 7 is energized and a suitable current generated in the armature 8, which passes from brush 11 through the primary coil 13 of the 95 transformer 14 back to the brush 12. As the resistance of the rotation of the shaft 9 increases greatly when the key 10 is closed and the field 6 energized the kinetic energy stored up in the revolving fly wheel is utilized to take care of this sudden increase of resistance or drag and as the key is only closed when messages are being sent and then only for short periods of time it is possible to keep the shaft 9 rotating approximately uniformly at a speed, while the apparatus is in use, which they could not maintain if

105

the field 6 were energized continuously instead of intermittently as described. It will therefor be apparent that by my improvement it is possible to secure a materially greater range of wireless communication from power exerted by men laboring at the operating cranks than would otherwise be possible.

While I have shown and described the preferred form of my apparatus it is to be understood that numerous changes may be made in the form and details of construction without departing from the spirit of my invention or the scope of the subjoined claims.

Having described my invention, I claim:—

1. In transmitting apparatus for wireless signaling, an alternating current generator to supply the transmitting current, a direct current generator adapted and arranged to supply current to the field of the alternating current generator, a transmitting key in circuit with the direct current generator, and the field of the alternating current generator whereby the field of the alternating current generator is energized by the direct current generator only when the key is closed, the armature windings of both generators being mounted upon the same armature shaft, and means for storing up surplus energy imparted to the shaft when the key is open and imparting it to the shaft when the key is closed whereby the armature shaft may be operated at a substantially uniform speed from a small energy source.

2. In transmitting apparatus for wireless signaling, an electric generator, a separate source of current adapted to energize the field of said generator, a transmitting key between the said field and the source of current and a fly wheel fixed upon the armature shaft of the generator adapted to store up excess energy imparted to the shaft when the key is open and to impart it to the shaft when the key is closed whereby the armature shaft may be operated at a substantially uniform speed from a small energy source.

3. In transmitting apparatus for wireless signaling, an electric generator, a separate source of current adapted to energize the field of said generator, a transmitting key between the said field and the source of current, a fly wheel fixed upon the armature shaft of the generator adapted to store up excess energy imparted to the shaft when the key is open and to impart it to the shaft when the key is closed, and manually operable means to rotate the said armature shaft.

4. In transmitting apparatus for wireless signaling, an electric generator to supply the transmitting current, an electric generator adapted and arranged to act as an exciter for the first named generator, the armature of the exciter being connected in parallel with the fields of the exciter and

transmitting generator, a transmitting key in circuit with the field of the transmitting generator, common manually operated means to effect the rotation of the armatures of the exciter and transmitting generator, and means for storing up energy from such rotation means when the transmitting key is open and utilizing it in the rotation of the armatures when the key is closed.

5. In transmitting apparatus for wireless signaling, an electric generator to supply the transmitting current, an electric generator or exciter adapted and arranged to supply current to the field of the transmitting generator, a transmitting key in circuit between the said field and the exciter whereby the said field is energized by the exciter only when the key is closed and means for storing up surplus energy imparted to the shaft of the exciter when the key is open and imparting it to the shaft when the key is closed whereby such armature shaft may be operated at a substantially uniform speed from a small energy source.

6. In transmitting apparatus for wireless signaling, an electric generator to supply the transmitting current, an electric generator adapted and arranged to act as an exciter for the first named generator, a key in circuit between the exciter and the transmitting generator, common manually operated means to effect the rotation of the armatures of the transmitting generator and exciter, means for storing up surplus energy imparted to the armature of the exciter when the key is open and imparting it to such armature when the key is closed whereby such armature may be operated at a substantially uniform speed from a small energy source.

7. In transmitting apparatus for wireless signaling, an electric generator to supply the transmitting current, an electric generator or exciter adapted and arranged to supply current to the field of the transmitting generator, a transmitting key in the circuit between the said field and the exciter whereby the said field is energized by the exciter only when the key is closed, the armature windings of the two generators being mounted upon the same armature shaft, and means for storing up surplus energy imparted to the said shaft when the key is open and imparting it to said shaft when the key is closed whereby the said shaft may be operated at a substantially uniform speed from a small energy source.

8. In transmitting apparatus for wireless signaling, an electric generator to supply the transmitting current, an electric generator or exciter adapted and arranged to supply current to the field of the transmitting generator, a transmitting key in the circuit between the said field and the exciter whereby the said field is energized by

the exciter only when the key is closed, the armature windings of the two generators being mounted upon the same armature shaft, and a fly-wheel fixed upon the said shaft whereby when signals are being sent, the armature shaft may be operated at a substantially uniform speed from a small energy source.

9. In transmitting apparatus for wireless signaling, an alternating current generator to supply the transmitting current, a direct current generator adapted and arranged to supply current to the field of the alternating current generator, a transmitting key in circuit with the direct current generator and the field of the alternating current generator whereby the field of the alternating current generator is energized by the direct current

generator only when the key is closed, means to effect the rotation of the armatures of the 20 alternating current and direct current generators and means for storing up surplus energy imparted to the armature shaft of the alternating current generator when the key is open and imparting it to the said shaft 25 when the key is closed whereby the armature of the alternating current generator may be rotated at a substantially uniform speed from a small energy source.

In testimony whereof I affix my signature 30 in presence of two witnesses.
